UNITED STATES PATENT OFFICE

GEORGE W. THOMAS, OF PITTSBURGH, PENNSYLVANIA, ASSIGNOR TO H. H. ROBERTSON COMPANY, OF PITTSBURGH, PENNSYLVANIA, A CORPORATION OF PENNSYLVANIA

BUILDING CONSTRUCTION

Application filed December 19, 1928. Serial No. 327,085.

This invention relates to a building construction and is herein shown as embodied in a glazing construction capable of being used in the roof or side wall of the building.

5 The invention will be hereinafter specifically described with reference to a glazing construction and has for its object to provide a glazing unit which can be substituted for the stationary panes of glass of a window sash and particularly of a stationary window sash forming part of the side wall or roof of a building, whereby the side walls or roof may be provided with movable panes of glass for ventilating the building.

10 The invention also has for its object to accomplish this result without change in the construction of the window sash and at a minimum expense and in a minimum time.

To these ends, the glazing unit is provided 15 with a glass-carrying frame which is movably mounted in an open supporting frame, which latter is constructed so as to be capable of being substituted for the normally fixed glass in the sash of the latter, and particularly when the said sash is made of metal.

The glass-carrying frame is preferably pivoted to the supporting frame and provision is made for preventing the entrance of rain, snow, dust, etc. when the movable glass-carrying frame is in its closed position as 20 will be described.

These and other features of this invention will be pointed out in the claims at the end of this specification.

25 In the accompanying drawing illustrating the invention

Fig. 1 represents a portion of a side wall of a building provided with a glazing construction having stationary panes of glass and glazing units embodying this invention;

30 Fig. 2, an enlarged section on the line 2—2, Fig. 1 through adjacent stationary panes of glass;

35 Fig. 3, an enlarged section on the line 3—3, Fig. 1 through a movable glazing unit to illustrate the substitution of the said unit for a stationary pane of glass;

40 Fig. 4, a front elevation of the open supporting frame of the improved glazing unit;

Fig. 5, a side elevation of the frame shown in Fig. 4;

Fig. 12, an enlarged central section of the glazing unit with the glass-carrying frame 65 in its closed position, taken on the line 12—12, Fig. 1, and

Fig. 13, a side elevation of a portion of the glazing unit on an enlarged scale, with the glass-carrying frame in its open position. 70

Referring to the drawing 10 represents a side wall of a building provided with a glazing construction comprising stationary glass panes 12 and movable glass panes 13 of glazing units embodying the present invention 75 and shown as two in number.

Each glazing unit embodying the present invention comprises a glass-carrying frame 14 and an open supporting frame 15 in which the glass-carrying frame is movably mounted. 80

The open supporting frame 15 shown separately in Figs. 4 and 5 is constructed so as to enable it to replace a stationary glass pane 12 without changing the construction of the sash or framework to which the 85 stationary glass pane 12 is secured.

The open supporting frame 15 is also constructed so as to enable the glass-carrying frame 14 to be mounted therein and to be moved with relation thereto when it is desired to ventilate the building through the 90 side wall.

The frames 14, 15 are also preferably constructed so as to obtain a weather-tight fit or joint between the frames when the movable glass-carrying frame 14 is in its closed position. The frames 14, 15 are also preferably constructed so that the glass-carrying frame may be quickly and easily inserted into or removed from the supporting frame 15. 95 100

To these ends, the frames 14, 15 are preferably constructed as will now be described and as shown in Figs. 4 to 12 inclusive.

The supporting frame 15 is provided with 5 a top member, bottom member, and side members.

These members may and preferably will be cast in one piece of aluminum or other metal.

In the preferred construction herein shown, 10 the top member comprises a bar 20 (see Fig. 12) having at its rear end an upwardly extended flange 21 and at its front end a depending flange 22 from which extends rearwardly a horizontal flange 23 forming with the bar 20 and with the flange 22 a channel 24, which is open at its rear end and closed at its front end.

Each side member comprises a bar 25, which extends for the full length of the side 20 member, and is provided at its rear end with an outwardly extended flange 26 (see Figs. 5 and 8), which forms a vertical continuation of the flange 21 of the top member, and extends the full length of the bar 25. The front 25 end of the bar 25 is provided with a flange 27 (see Fig. 8), which extends laterally inward and has at its end a rearwardly extended flange 28. The flanges 27, 28 are extended from the top member for a portion only of 30 the length of the side bars 25, and form with the upper portion of the bar 25 a channel 29, which is open at its rear end and closed at its front end.

The lower part of the side bar 25 is not 35 provided with a channel and is made narrower than the width of the front flange 27 of the upper part of the side bar. The lower part of the bar 25 is made thicker than the upper part as shown in Fig. 9 and is provided with the external flange 26 and with a 40 forwardly projecting flange 30.

The bottom member comprises a bar 31 (see Figs. 9 and 12) having at its rear end a downward extended flange 32 and an upwardly extended flange 33, and having at its 45 front end a forwardly extended flange 34.

The flange 21 of the top member, the flanges 26 of the side members and the flange 32 of the bottom member are located in the 50 same vertical plane and are of the same thickness and substantially the same thickness as the stationary glass panes 12 used in the window sash or framework, so that when a stationary glass pane 12 is removed from 55 the window sash or framework, the supporting frame 15 can be substituted therefor without change in said framework, and said supporting frame can be secured to the framework or sash by the same means with 60 which the stationary pane 12 is secured.

The side bars 25 are provided with rearwardly extended ears 36 to which the glass-carrying frame 14 is pivoted.

The ears 36 are attached to the lower unchanneled part of the side bars 25 and said

lower part terminates a short distance above a horizontal plane 37 through the center of the pivot holes 38 in said ears, and the flange 27 of each side bar is provided at its lower end with a curved portion 39 having the pivot 70 hole 38 in the ear 36 as a center.

The curved portion 39 terminates substantially in the same horizontal plane as the upper ends of the unchanneled lower part of the side bar 25, whereas the flange 28 which is extended rearwardly from the flange 27, terminates a substantial distance above the horizontal plane 37, so as to leave a space 40 between the lower end of the flange 28 and the upper end of the front extension or flange 80 30 on the lower part of the side bar, which space is of sufficient width or size to permit the lower part of the glass-carrying member 14 to be passed through the space 40 and into 85 position to be pivotally secured to the ears 36 by pivot pins 41, after the manner represented in Figs. 12, 13.

The glass-carrying frame 14 comprises top and bottom members and connecting side members. The top member comprises a cross 90 bar 44 (see Figs. 10 and 12) having at its front end an upwardly extended flange 45 and at its rear end a downward extended flange 46.

The side members of the frame 14 are provided with an unchanneled upper portion and with a channeled lower portion.

The unchanneled upper portion comprises a substantially wide bar 47 (see Figs. 6 and 10) having at its front end an outwardly extended flange 48 and at its rear end an inwardly extended flange 49.

The channeled lower portion comprises extensions of the bar 47, the inwardly extended flange 49, and of the outwardly extended flange 48, and the latter is provided at its outer end with a rearwardly extended flange 50 (see Figs. 10 and 11), which forms with the bar 47 a channel 51, which is open at its rear and closed at its front by the lower part 105 of the flange 48.

The bottom member comprises a horizontal bar 52 (see Figs. 10 and 12) having at its rear end an upwardly extended flange 53, and at its front end with a downward extended flange 54, which latter is provided with a rearwardly extended flange 55, which forms with the bar 52 a horizontal channel 56 which is open at its rear and closed at its front by 115 the flange 54.

The side members of the glass-carrying frame 14 are provided with ears 58 having holes 59 for the reception of the pivot pins 41, by which said frame is pivoted to the ears 36 120 on the supporting frame 15.

The flange 50 of the channeled lower part of the frame 14 is extended above the pivot 41 and the front flange 48 is provided with a curved projection or lug 60 which co-operates 130

with the curved portion 39 of the supporting frame 15.

The inwardly extended flanges 46, 49, 53 are in the same plane and form a bed for supporting the pane 13 of glass or like light-transmitting material. The glass pane 13 may be secured to the bed by means of clamping members 63 shown as angle metal members which are fastened to the bed by bolts 64 and nuts 65 (see Fig. 12).

The glass pane 13 may and preferably will be provided at its top, bottom and side edges with channeled cushions 66, preferably felt saturated with asphalt, the side walls of said cushions being interposed between the clamping members 63 and the glass and between the bed and the glass. The cushions yieldingly support the glass and the clamps permit the glass to be readily removed in case of breakage.

The clamping members 63 and cushioning members 66 may cooperate with all of the flanges comprising the bed but in the present instance are shown in Fig. 12 as co-operating with the top and bottom flanges 46, 53.

From the above description, it will be observed that the glass pane 13 is carried by a frame 14, which is movably mounted in an open supporting frame 15, and that the latter frame is provided with outwardly extended flanges which are located in the same plane and are made of a thickness equal or substantially equal to the thickness of the stationary glass panes 12, and the dimensions of the supporting frame are the same or substantially the same as those of the stationary glass panes 12, so that a side wall 10 or other portion of a building which is provided with a stationary glazing construction having a plurality of stationary glass panes 12, and which affords no opportunity for ventilating the building through such glazing construction, may have one or more of the stationary glass panes removed and replaced by the glazing unit herein shown and described without necessitating any change in the stationary glazing construction, and said glazing unit enables the building to be ventilated in the side wall.

The improved glazing unit may be substituted for the stationary glass pane in its assembled condition, shown in Fig. 12, or as is preferred, the open supporting frame 15 may be first secured to the sash or frame from which the stationary glass pane 12 has been removed, and the glass-carrying frame 14 inserted into the stationary frame and pivotally secured thereto.

By reference to Fig. 12, it will be observed that the portion of the stationary frame 15 above the pivots 41 and on the outside of the building is channeled and co-operates with the unchanneled upper portion of the movable glass-carrying frame 14 to form a practically weather-tight fit or joint between the

upper portions of said frames, when the movable frame is in its closed position.

It will also be observed that the portion of the movable frame 14 below the pivots, which is also on the outside of the building is channeled and co-operates with the unchanneled lower portion of the supporting frame 15 to form a practically weather-tight fit or joint between the lower portions of said frames when the movable frame is in its closed position.

The glazing unit above described is capable of replacing a stationary glass pane in a window sash or frame made of wood, and in which the stationary glass pane is retained by brads or like devices and putty, but it is especially adapted for use in factories and like buildings having the window sash or frame composed of metal bars.

In Fig. 2, is illustrated in cross section a portion of a known glazing construction having a metal sash, said portion comprising substantially parallel metal members shown as angle members 70, which are vertically arranged and each of which is overlapped on its front face by two of the stationary glass panes 12, which latter are pressed against a metal member 70 by a cap member 71, which is held in place by a nut 72 on a threaded stud 73 projecting from the metal member 70, said glass members being cushioned and sealed by strips 74, 75 of asphaltic felt, or the like.

In Fig. 3, is illustrated the same glazing construction, with one of the stationary glass panes 12 replaced by the glazing unit herein described.

By reference to Fig. 3, it will be seen that the supporting frame 15 has its side flanges 26 overlapping the adjacent metal sash member 70 and each side flange 26 has co-operating with it the cushions 74, 75 and cap member 71, the same as these parts co-operate with the stationary glass pane 12 in Fig. 2.

It will also be observed that no change in the stationary metal sash 70 or in the parts co-operating therewith is required to enable the substitution to be made and the permanently closed or stationary non-ventilating glazing construction to be converted into a ventilating glazing construction in a minimum time and at a minimum expense and further in any portion of the building where additional ventilation is desired or required.

The ventilating construction can be removed from one location in the building and used in a different location in the building, when necessary or desired, or it may be replaced by a stationary glass pane 12 if desired.

The invention has been particularly described with reference to a glazing construction, but it is not desired to limit the invention in this respect, as the glass member 13 may be replaced by an opaque member and

the construction employed for ventilating portions of the building in which a glazing construction is not required or desired.

In the present instance the movable frame 5 of the ventilating construction is shown as pivoted to the open supporting frame between the ends of the latter, but it is not desired to limit the invention to any particular location of the pivots.

10 One embodiment of the invention is herein shown, but it is not desired to limit the invention to the particular construction shown.

What is claimed is:

1. In a glazing construction, in combination, an open supporting frame provided with an external flange for attachment to a window sash, and a glass-carrying frame pivoted to said supporting frame and movable with relation to the said supporting frame to open 20 and close the opening therein said flange being of a thickness substantially that of the glass pane of the window.

2. In a glazing unit, in combination, an open supporting frame having top, bottom 25 and side members provided with external flanges for attachment to a window sash, and a glass-carrying frame movably mounted on said supporting frame and co-operating with the latter to open and close the opening in 30 said supporting frame, said flanges being of a thickness substantially that of the glass pane of the window.

3. In a building construction, in combination, two sets of substantially parallel metal 35 supporting members, one set extending at right angles to the other to form a series of open frames, a plurality of glass panes fitting said open frames, metal clamping members secured to the supporting members and 40 cooperating with the glass panes to clamp them in said open frames, and a glazing unit capable of being substituted in said construction for one of the glass panes, comprising an open supporting frame having a marginal 45 portion capable of fitting into one of the aforesaid open frames and to be clamped therein by said clamping members, and a glass carrying frame movably mounted upon the supporting frame to open and close the 50 opening in the supporting frame and cooperating with the latter to close said open frame.

4. In a building construction, in combination, two sets of substantially parallel metal 55 supporting members, one set extending at right angles to the other to form a series of open frames, a plurality of glass panes fitting said open frames, metal clamping members secured to the supporting members and 60 cooperating with the glass panes to clamp them in said open frames, and a glazing unit capable of being substituted in said construction for one of the glass panes, comprising an open supporting frame provided with a marginal flange of a thickness substantially 65 that of the glass pane for which the glazing

unit is substituted and capable of fitting into one of the aforesaid open frames and to be clamped therein by said clamping members, and a glass carrying frame movably mounted upon the supporting frame to open and close the opening in the supporting frame and cooperating with the latter to close said open frame.

5. As a new article of manufacture, a glazing unit capable of being bodily substituted for the glass pane of a window, comprising an open supporting frame of substantially the size of the glass pane and whose marginal portion is of a thickness substantially that of the glass pane to enable it to be set in the window in the same manner as the glass pane, and a movable glass carrying frame mounted within the open supporting frame to form a unitary structure therewith.

In testimony whereof, I have signed my name to this specification.

GEORGE W. THOMAS.
